UNITED STATES PATENT OFFICE.

THOMAS R. MACKEY, OF ALLEGHENY, ASSIGNOR TO THE UNITED STATES BAKING COMPANY, OF PITTSBURG, PENNSYLVANIA.

DESIGN FOR A CRACKER.

SPECIFICATION forming part of Design No. 22,990, dated December 26, 1893.

Application filed November 28, 1893. Serial No. 491,808. Term of patent 14 years.

To all whom it may concern:

Be it known that I, THOMAS R. MACKEY, a resident of Allegheny, in the county of Allegheny and State of Pennsylvania, have invented a new and original Design for Crackers; and I do hereby declare the following to be a full, clear, and exact description thereof.

My design relates to crackers.

It consists in a cracker having the shape of a keystone and having depressions at intervals on its surface.

In the accompanying drawing the figure is a plan view of a cracker embodying the design.

15 The cracker *a* embodying the design has the shape of a keystone, as shown in the

drawing, and it is further provided with the depressions *b* at intervals on its surface, such depressions breaking the continuity of the oven surface of the cracker as shown in the 20 drawing.

What I claim, and desire to secure by Letters Patent, is—

The design for crackers herein shown and described.

In testimony whereof I, the said THOMAS R. MACKEY, have hereunto set my hand.

THOMAS R. MACKEY.
